UNITED STATES PATENT OFFICE.

DANIEL BUTTS DUNLOP, OF PETERSBURG, VIRGINIA.

SUBMARINE BOMB.

1,194,726.

Specification of Letters Patent. Patented Aug. 15, 1916.

Application filed January 29, 1916. Serial No. 74,977.

To all whom it may concern:

Be it known that I, DANIEL B. DUNLOP, a citizen of the United States of America, residing in the city of Petersburg, county of 5 Dinwiddie, State of Virginia, have invented certain new and useful Improvements in Submarine Bombs, of which the following is a specification.

The present invention relates to a submarine bomb of the general type shown and described in my U. S. Patent No. 1,161,636, of November 23rd, 1915; in fact, this invention consists in specific improvements on my patented device.

15 The patented bomb is designed for use against sub-marine craft and is intended to be dropped from a distance above the water, as from an aeroplane or other air craft, to be exploded within a predetermined period 20 of time after it strikes the water, or more particularly, it consists of a container or vehicle holding an explosive charge with detonating means and a time measuring instrument controlling the detonating means 25 with means for releasing or tripping the time measuring instrument when the bomb strikes the surface of the water. As disclosed in the drawings in this application and in the previous patent, the tripping 30 means includes a wing or wings held in distended position by means of a spring and forced inward when they come in contact with the water and a lock connected to the wings and controlling the timing mechanism 35 to release the timing mechanism when the wings strike the water. As long as there is sufficient pressure on the wings, the timing mechanism will continue to operate, but in case the bomb strikes the sub-marine or rests 40 on the bottom, it is suggested that by relaxation of the pressure on the wings, the lock might be returned to its initial position in time to arrest the action of the timing mechanism and prevent the explosion of the 45 bomb.

The present invention relates to a detent for holding the lock in inoperative position after it has once been actuated to release the timing mechanism so that the explosion can 50 not be prevented or retarded or otherwise affected by relaxation of pressure on the wing or blade.

The invention also relates to other details, as a specific means for holding the detonating 55 hammer in retracted position and re-

leasing it to fire the charge, and to other details hereinafter described.

In the accompanying drawings, I have shown a sub-marine bomb embodying the features of my invention, in which— 60

Figure 1 is an elevation; Fig. 2 is a plan; Fig. 3 is a horizontal section; and Fig. 4 is a transverse section, both through the chamber containing the mechanism; and Fig. 5 is an elevation of a detail. 65

Referring to the drawings by numerals, the device, as illustrated, consists of a cylindrical casing 1, preferably pointed at the lower end at 2 and having a plurality of external blades or wings 3 inclined upward 70 and outward from the surface of the casing, being, as shown, pivoted at 4 to the surface of the casing, and connected at their upper ends to the casing by sliding bars 5 carrying helical springs 6 which as shown bear at 75 one end against the casing and at the other end against the wings or blades and hold the wings normally in distended position. The sliding bars 5 pass inward through the walls of the casing by way of packed joints 80 or openings 7, and are guided by means of apertured plates 6', provided for this purpose. These sliding or locking bars 5 are provided each with a lug 8, which in the locked position of the apparatus, see Fig. 3, 85 engages a corresponding notch 9 in the locking wheel 10 secured to and turning with the rotating shaft 11 of the clock-work 12 which constitutes the timing element referred to. The lugs each enter the notches 90 on the side opposite that on which the bar carrying that particular lug engages the wing or blade and the lock is released when the bars are forced in by pressure on the 95 wings.

The parts are shown in unlocked position in Fig. 4, the springs being compressed and the bars 5 thrust inward, as by the pressure on the wings or blades 3. This figure illustrates in detail the operation of the detents 100 13 which constitute one of the novel features of the invention. The detents referred to are shown in the form of sliding plates, illustrated separately in Fig. 5, the plates, as shown, being of inverted U-shape and 105 hung on the locking bars so that when they encounter the flat top surfaces of these bars, they have no effect on the operation of the mechanism. In order to hold the sliding or locking bars in inoperative position when 110

- the clock-work is released by pressure on the wings and prevent interference with the timing mechanism when the pressure on the wings is relaxed, these bars are each notched 5 at 14 at a point which is brought beneath the detent as the bars move inward releasing the clock-work, and the detents, as arranged enter and engage the notches and hold the lugs 8 on the locking bars out of engagement 10 with the locking wheel 10.
- In the form of the invention shown, the 15 detents 13 are mounted in ways or pockets 15 provided for this purpose but they may be held in any suitable manner within the 20 scope of the invention and while they are shown as actuated by gravity, any suitable means may be provided for this purpose.
- The bomb casing, as shown, is divided 25 into two sections by the partition 16; on the upper side of the casing is the timing or tripping mechanism and on the lower side is the charge of explosive 17. In the partition there is a socket 18 for a primer 19 to be engaged by a suitable hammer or detonator 20 mounted in guide ways 21 and held in retracted position by engagement of a suitable detent 22 in the form of a lever pivoted at one end at 23 and having a notch 24 to engage a corresponding notch 25 in 30 the plunger or detonator, the same being advanced by means of a spring 26 applied in the manner illustrated, or in any other suitable manner and normally held in retracted position by the detent 22 as described. In 35 the operation of the mechanism, the notched wheel 30 tends to rotate in the direction of the arrow but is held against rotation by the catch lever 31 which is in turn locked by the cam 32 carried by the clock mechanism.
- 40 When the clock, which is a quick-acting device preferably having the usual balance lever or detent removed, is released by withdrawal of the lugs 8 from the slots 9 in the wheel 10, the cam 32 is rotated, the lever 31 45 is in turn released and thrown out of the notch 33 in the wheel 30 so that the gear 34 on the same shaft is likewise released, releasing the gear 35 carried by the spring 36 and causing the dog 37 which is fastened to 50 the shaft 38 of the wheel 30 to be swung about the shaft, striking the end of the locking detent 22 which is thus swung up to the dotted position, releasing the detonator and firing the charge.
- 55 It will be apparent that with the use of this device, even if the bomb should fall in shallow water and lie on the bottom or be arrested in its progress by contact with the hull, releasing the pressure on the wings, 60 the sliding bars or locking bars 6 will be

locked in retracted position by detents 13 so that the lugs cannot engage the locking wheel 10, the timing mechanism will continue to operate and the explosion will take place according to the adjustment of the timing mechanism in a predetermined period after the bomb passes through the surface of the water.

Having thus described my invention, what I claim and desire to secure by Letters Patent is:

1. In a submarine bomb, in combination, a casing having wings or blades, an explosive charge in the casing, detonating means for the charge, means for holding the detonating means in retracted position, time measuring means for controlling the said means, means for locking the time measuring means, connections from the lock to the wings to release the lock when the bomb enters the water, and detents adapted to engage the locking means when it is released and hold it in unlocked position.

2. In a submarine bomb, in combination, a casing, an explosive charge therein, means for detonating the explosive charge, time measuring means for locking the detonating means, means for locking the time measuring means, and wings or blades controlling the locking device to release the lock when the bomb enters the water and a detent in the form of a sliding latch engaging the locking means to hold it in inoperative position during the operation of the time measuring means.

3. In a submarine bomb, in combination, a casing, an explosive charge in the casing, a percussion primer for igniting the charge, a hammer with means tending to advance the hammer into contact with the primer, means for holding the hammer in retracted position, time measuring means for operating the said means to release the hammer after a predetermined period, means locking the time controlling means, and means for releasing the lock when the bomb enters the water, the device for holding the hammer in retracted position consisting of a pivoted lever swinging transversely to the hammer's stroke, the time measuring means being provided with a swinging dog to engage the lever and release the hammer.

Signed by me at Petersburg, Dinwiddie county, Virginia, this 25th day of January 1916.

DANIEL BUTTS DUNLOP.
